UNITED STATES PATENT OFFICE

LUTHER RINGER, OF UNION SPRINGS, NEW YORK, ASSIGNOR TO SYRACUSE WASHING MACHINE CORPORATION, OF SYRACUSE, NEW YORK, A CORPORATION OF DELAWARE

IRONER

Application filed October 9, 1929. Serial No. 398,386.

This invention relates to a new and improved ironer.

My invention is particularly directed to a means for supporting the ironing shoe which is moved into and out of contact with the ironing roll.

In ironers of the type here described, the shoe is intermittently and automatically moved into and out of contact with the roll to permit the insertion therebetween of the goods to be ironed and then to perform the ironing operation.

It is usual in ironers of this type to provide a means such as an electrical resistance coil for heating the ironing shoe and when this is the case, the clothes being ironed should not be allowed to remain in contact with the heated shoe any longer than is necessary to perform the ironing operation for otherwise there is danger of scorching or burning the clothes.

In order that the shoe may be manually moved out of contact with the roll in order to permit the removal of any clothes which may be between them, it is desirable that the shoe be so connected to the operating mechanism that such manual control is permitted.

For example, if through the burning out of a fuse or any other cause, the operation of the ironing machine should be stopped at a time when a piece of material was under pressure between the roll and the heated shoe, it is essential that some means be provided so that the operator may separate the roll and the shoe and remove the goods before they are damaged.

Also, occasionally goods may be started between the roll and the shoe in the wrong direction or in a creased condition and it is then desirable to provide a convenient means whereby such clothes may be released and started over again in the proper shape.

The main object of my invention is to provide a supporting means for the shoe of an ironing machine which normally will permit the shoe to be automatically moved towards and from the roll during the operation of the machine but which is so designed that the shoe may be manually disconnected from its driving means and be moved out

of contact with the roll irrespective of the continuing operation of the mechanism of the ironing machine.

Another object is to provide a support for a shoe which is of such a design that when the shoe has been manually disconnected from its driving means, it will be automatically re-connected to such driving means when, after interruption, the driving mechanism is again placed in operation.

Another object is to provide a supplementary means for aiding in supporting the weight of the ironer roll and shoe to relieve the ironer shaft and its bearings from strain.

Other objects and advantages relate to the size, shape and arrangement of parts all as will more fully appear from the following description taken in connection with the accompanying drawings in which:—

Figure 1 is a top plan view partially broken away of my improved ironing machine.

Figure 2 is a section on line 2—2 of Figure 5.

Figure 3 is a section on line 3—3 of Figure 1.

Figure 4 is a section on line 4—4 of Figure 1.

Figure 5 is a section on line 5—5 of Figure 2.

Figure 6 is a section on line 6—6 of Figure 5.

Figure 7 is a section on line 7—7 of Figure 6.

The ironing machine 1 comprises a gear casing 2 with a roll 12 extending laterally therefrom and with a shoe 11 in parallel relation with roll 12 and operatively connected to a shaft 5 which extends laterally from the gear casing 2.

Shaft 5 is journaled in a tubular bearing 6 which has one end extending into gear casing 2 and which has the outer end supported in a saddle 7. On the outer end of shaft 5 is rotatably mounted a yoke 8. On the upper end of yoke 8 is pivotally mounted a shoe support 9 to the forward end of which and above the pivot 10 is secured the shoe 11.

Shoe support 9 is provided with a hand hold 9' to afford an easy means of returning

the shoe 11 to the operative position, if it is desired to do so manually.

Shoe 11 is curved in cross section with its inner face conforming to the contour of the roll 12, roll 12 carrying on its periphery a padding 13. Within shoe 11, I provide a heating resistance unit 14, connected, as by a cable 15, to a source of potential not shown.

A spring 16 has its upper end secured to the rear face of shoe 11 and has its lower end bearing against the inner face of yoke 8 to hold shoe 11 in the raised position when the same is out of contact with roll 12.

Between the sides of yoke 8 and pinned to shaft 5 as by a pin 17, I provide a member 18 which has its outer end provided with an aperture 19 through which extends a rod 20.

The lower end of rod 20 is provided with a transverse pin 21 normally abutting a curved guide 22 on member 18.

The upper end of rod 20 is provided with an adjusting nut 23. A spiral spring 24 has one end abutting nut 23 and has its lower end abutting member 18 to normally urge rod 20 in the raised position with pin 21 abutting guide 22.

On the lower end of yoke 8 is pivotally mounted as by a pivot 25, a dog 26 which carries on its upper end a hooked portion 27 adapted to normally engage the pin 21 to lock the yoke 8 to the member 18.

A spring 28 has one end secured to member 18 with the other end secured to dog 26 to releasably hold hook 27 in registration with pin 21. With the parts in the normal position, any movement transmitted to member 18 through shaft 5 will be transmitted to yoke 8.

On the upper end of yoke 8 is pivotally mounted as by a pivot pin 29, a bell crank 30. In the upper end of bell crank 30, I provide a vertically extending shaft 31 carrying a knob 32' at its upper end. The other arm 32 of bell crank 30 is in engagement with a rod 33 slidably mounted in the upper end of yoke 8 and having its lower end pivotally mounted in the outer end of dog 26.

The lower end of bell crank 30 has a stop 34 which abuts the yoke 8 to limit the movement of bell crank 30 in one direction.

With the parts in the position just described, member 18, yoke 8 and shoe 11 will be actuated as a unit through the movement of shaft 5 which movement will be herein-after described but which is adapted to move shoe 11 towards and from roll 12.

When it is desired to release yoke 8 from member 18 so that yoke 8 carrying shoe 11 may be moved about shaft 5 to move shoe 11 out of engagement with roll 12, the bell crank 30 is moved about its pivot by means of shaft 31 and this movement will cause the end 32 of bell crank 30 to move downwardly pushing before it rod 33.

The downward movement of rod 33 will cause dog 26 to be moved about its pivot 25

to carry hook 27 out of engagement with pin 21 to break the connection between yoke 8 and member 18.

The position of parts after this initial movement of shaft 31, is indicated in light dotted lines on Figure 3. After this initial movement has been completed, shaft 31 may be moved still further in the same direction causing yoke 8 to pivot about shaft 5 to move shoe 11 out of engagement with roll 12. The position of parts after this second movement of shaft 31 has been accomplished is indicated in heavy dotted lines on Figure 3.

For the purpose of limiting this latter movement of yoke 8, I provide on yoke 8, a pin 35 which is adapted to contact with a finger 36 provided on saddle 7.

With the parts in the last described position, it will be noted that the hook 27 is beneath but in the path of movement of the pin 21 when the same is moved downwardly due to the rotary movement of member 18 on shaft 5 so that when such movement of member 18 subsequently takes place through the operation of the mechanism about to be described, pin 21 will ride downwardly past hook 27 due to the fact that it will cause the pivotal movement of dog 26 against the action of spring 28, and after pin 21 has moved downwardly beneath hook 27, spring 28 will cause dog 26 to move about its pivot to bring hook 27 into registration with pin 21 so that the parts will become locked in the initially described operative position and any further movement of member 18 will cause yoke 8 and shoe 11 to be moved with it as a unit.

The mechanism provided for operating the roll 12 and the shaft 5 comprises a shaft 37 journaled in gear casing 2 and having mounted thereon a worm gear 38 which is in mesh with a worm 39 carried on the armature shaft of a motor 40 which motor 40 is, for convenience and compactness, mounted in vertical position on gear casing 2.

On shaft 37 is rotatably mounted a cam member 41 which is positioned in the open end of a jaw arm 42 which is secured to the inner end of shaft 5, as by a pin 42'.

On the side of cam member 41 which faces worm gear 38 is pivotally mounted a clutch dog 43 as by a pivot pin 44. On the hub 45 of worm gear 38 is secured as by a pin 46, a clutch member 47 provided on its periphery with spaced recesses 48 adapted to receive a finger 49 carried on dog 43.

A spring 50 has one end secured to cam 41 as by a pin 51 and has its other end secured to dog 43 to normally move dog 43 about its pivot to bring finger 49 in registration with a recess 48.

When dog 43 on cam 41 is in registration with clutch member 47, the cam 41 will be operatively connected to the worm gear 38 so that the rotation of such gear 38 will cause the rotation of cam 41.

The rotation of cam 41 will in turn cause an oscillating movement of jaw arm 42 which oscillating movement will be communicated to shaft 5.

5 For the purpose of holding dog 43 out of registration with clutch member 47 so that cam 41 will be at rest, I provide an arm 52 secured to one end of a shaft 53 which is pivotally mounted in gear casing 2.

10 In the normal position, the arm 52 is in the path of movement of dog 43 so that the latter is held out of contact with the clutch member 47.

15 The arm 52 is normally held in this last described position by means of a spring 54. On the outer end of shaft 53, I provide an operating handle 55 by means of which shaft 53 may be rotated a limited distance to move arm 52 out of the path of movement of dog 43 20 to permit the same to be brought into operative contact with clutch member 47 through the operation of spring 50.

25 The dog 43 has its opposite ends extending outwardly so that they will alternately come into contact with arm 52 so that if arm 52 is moved out of contact with the end of dog 43 with which it was in engagement, the cam 41 will begin to rotate and will continue to rotate until the opposite end of dog 43 comes into registration with arm 52, the latter meanwhile having been allowed to return to the normal position by the releasing of operating handle 55.

It will thus be seen that the rotation of cam 41 will be stopped after it has completed one-half of a revolution.

30 Adjacent the rear face of worm gear 38 and rotatably mounted on shaft 37, I provide a gear 56 having the side which is adjacent gear 38 provided with clutch teeth 57 adapted to engage the clutch teeth 58 provided in the face of gear 38.

35 Gear 56 is held between collars 59 and 59' which are secured to shaft 37, and shaft 37 has a spring 58' normally urging it in a direction to cause clutch teeth 57 to engage clutch teeth 58. A description of the operation of the specific clutch comprising members 57 and 58 is not essential to the description and explanation of my invention here disclosed. It is sufficient to state that the clutch teeth 57 and 58 are normally in engagement during the operation of the machine so that roll 12 will be rotated through gear 56 which is in mesh with a gear 60 journaled in gear casing 2, which gear 60 is in turn driven by suitable gearing not shown.

40 Such specific clutch and operating mechanism therefor is disclosed and claimed by me in my copending application on an ironer filed November 29, 1929, Serial No. 410,484.

45 For the purpose of providing a convenient means for controlling the heating unit 14

in shoe 11, I provide on gear casing 2, a switch 61 in the electrical circuit.

Operation

When it is desired to use my improved ironer, the motor 40 is connected in any convenient way to a source of potential, none here being shown, although it is usual to provide a lead as 62 leading from the motor to any convenient plug in the house lighting circuit. The switch, 61 is then manipulated to send electrical current to the resistance 14 in shoe 11.

When it is desired to use my improved ironer, the motor 40 is connected in any convenient way to a source of potential, none here being shown, although it is usual to provide a lead as 62 leading from the motor to any convenient plug in the house lighting circuit. The switch, 61 is then manipulated to send electrical current to the resistance 14 in shoe 11.

50 A switch not shown is then turned to the "on" position causing the motor to rotate worm gear 39 and this, through gear 38, gear 56, gear 60 and an internal gear not shown on roll 12 will cause the rotation of roll 12. The clutch dog 43, not being operatively connected to the clutch member 47, will not cause 55 rotation of the cam 41 and therefore the shaft 5 will remain at rest.

55 In order that an article may be passed between the roll 12 and shoe 11 for the purpose of ironing the same, it is necessary to 60 turn the handle 55 which will move the member 52 from the path of the dog 43 to permit the same to engage with the clutch member 47. As heretofore described, this will cause the rotation of cam 41 which through fork 95 42 will cause a reciprocating movement of shaft 5 and this, in turn, will cause shoe 11 to be moved towards and from roll 12. When shoe 11 is in spaced relation to roll 12, the article to be ironed may be placed in position 100 with its front edge underlying shoe 11.

65 The rotation of roll 12 will carry the article downwardly between it and the shoe 11 and at the same time, the shoe 11 will be moved towards roll 12 and will be temporarily held 105 there under a predetermined pressure, the continuing rotation of roll 12 carrying the article downwardly and beyond shoe 11.

70 The movement of shoe 11 towards and from roll 12 is intermittent due to the fact that 110 when the dog 43 has been released from the member 52, it will again engage such member 52 after one-half of a revolution of the cam 41 to withdraw dog 43 from clutch member 47 and interrupt the movement of cam 41. 115

75 With the parts in position shown in Figure 2 with the high side of cam 41 against the lower arm of jaw member 42, the shaft 5 will have been rotated to the greatest extent 120 in an anti-clockwise direction and the shoe 11 will be held firmly against the roll 12 as indicated in Figures 3 and 4. When by the manipulation of handle 55, the dog 43 is permitted to engage clutch member 47, the cam 41 will make a one-half revolution which will bring the high side of such cam 41 in registration with the upper part of jaw member 42. In this position, the shaft 5 will have 125 been rotated the greatest distance in a clock- 130

wise direction and shoe 11 will have been moved away from roll 12.

An article may then be placed upon roll 12 and handle 55 again manipulated to permit dog 43 to engage clutch member 47 and rotate cam 41.

The half rotation of cam 41 which will then take place will bring the high side of cam 41 again into registration with the lower 10 arm of jaw member 42 and this, in turn, will move shoe 11 into ironing contact with roll 12 to iron the article as it passes between shoe 11 and roll 12. This operation may be repeated as often as desired.

15 To illustrate the operation of the manual release of shoe 11 and the automatic return of the same, I will assume that the apparatus has been stopped with the parts in the position shown in Figures 2, 3 and 4, at which 20 time, the shoe 11 is in pressure contact with roll 12, and that the electrical circuit running to the machine has been broken so that cam 41 cannot be caused to rotate by the manipulation of handle 55.

25 If, under these circumstances, an article is positioned between shoe 11 and roll 12, it would become scorched or burned if left in that position due to the fact that shoe 11 has been heated by resistance 14.

30 In order to remove such article, the shaft 31 is manipulated in the manner heretofore described to move the parts from the position shown in heavy lines on Figure 3 to the position shown in heavy dotted lines on Figure 3 in which position the shoe 11 is in spaced relation to the roll 12.

If, with the parts in this last described relation, the electrical circuit is again completed, handle 55 may be manipulated to 40 cause one-half of a revolution of cam 41 to bring the high side thereof into contact with the upper arm of fork member 42 which will cause the rotation of shaft 5 in clockwise direction. This rotation of shaft 5 will carry 45 the outer end of member 18 downwardly to cause pin 21 to pass beyond hook 27 on dog 26, and pin 21 will then engage hook 27 to lock yoke 8 to member 18.

If handle 55 is then again manipulated, 50 cam 41 will be caused to rotate to bring its high side in registration with the lower arm of jaw member 42 and this will cause the rotation of shaft 5 in an anti-clockwise direction, and this rotation of shaft 5 will cause 55 the outer end of member 18 to be carried upwardly moving with it yoke 8 and shoe 11, and shoe 11 will be brought again into contact with roll 12.

The shoe 11 has been described as being 60 held against roll 12 under pressure which is true, but the pressure exerted by shoe 11 against roll 12 depends upon the tension which is given to spring 24 by the manipulation of nut 23 so that if the resistance offered by the articles passing between shoe 11

and roll 12 is greater than the strength of spring 24, spring 24 will flex to permit shoe 11 to move slightly away from roll 12.

The flexure of spring 24 under these circumstances is permitted because shoe 11 is 70 carried on yoke 8 and yoke 8 is connected to member 18 by a hook 27 which is in registration with a pin 21 positioned in the lower end of rod 20, rod 20 being held in the raised position by the spring 24.

75 If the pressure exerted against shoe 11 and through yoke 8 and hook 27 to pin 21 is greater than the strength of spring 24, the rod 20 will be pulled downwardly which will permit the yoke 8 to move slightly about shaft 5 and this will cause the movement of shoe 11 from roll 12.

80 The provision of spring 24 and adjustable nut 23 permits a variation in the pressure exerted by shoe 11 against roll 12 so that the 85 amount of such pressure may be changed from time to time as desired to insure that the minimum necessary pressure is always exerted by shoe 11 on roll 12.

85 Although I have here shown my improved 90 shoe support as being used with a particular type of ironing machine, it will be understood that it is well adapted to be used with different types of ironing machines.

95 It will also be understood that the various sizes, shapes and arrangement of parts of the different parts of my device may be varied to a considerable degree to permit such device to be adapted to be used with various sizes, shapes and designs of ironing machines, 100 for although I have shown and described a specific structure and form of part as an exemplification of an embodiment of my device, I do not desire to restrict myself to the exact size, shape or arrangement of parts as 105 various changes may be made within the scope of the appended claims.

I claim:

1. In an ironing machine, a roller and a coacting shoe, a casing at one end of said roller forming a support therefor and having operating mechanism for said roller and shoe, a tube mounted at one end in said casing and extending outwardly therefrom substantially parallel with and beneath the axis of 110 said roller, a rock shaft journaled in said tube and having a portion projecting from the outer end thereof, means mounted upon the projecting portion of said rock shaft for actuating said shoe, and a supporting member 115 for said tube adjacent said shoe actuating means whereby the casing is held in upright position by said tube and supporting member.

120 2. In an ironing machine, a roller and a coacting shoe, a casing at one end of said roller having means for supporting the roller at one end, a tube mounted at one end in said casing and extending outwardly therefrom substantially parallel with the axis of said 125

75

5 roller, a rock shaft journaled in said tube and projecting at one end from the tube into the casing and projecting at its other end outwardly from the tube, means mounted on the outwardly projecting portion of said rock shaft for supporting and actuating said shoe, a supporting member for said tube adjacent said shoe supporting and actuating means, and mechanism within the casing for rotating the roller and rocking the rock shaft.

10 3. In an ironing machine, a casing, an ironing roll extending laterally from the casing, means for rotating the roll, a tubular member having one end secured in the casing and extending outwardly therefrom in parallel relation to the roll to a point approximately midway of the roll, a supporting member for the outer end of the tubular member, a shaft in the tubular member and having its outer 15 end extending beyond the outer end of the tubular member, an ironer shoe support secured to the outer end of the shaft, a shoe on the shoe support, and means for oscillating the shaft whereby the shoe is moved into and 20 out of contact with the roll.

25 4. In an ironing machine, a casing, an ironing roll extending laterally from the casing, means for rotating the roll, a tubular member having one end secured in the casing and extending outwardly therefrom in parallel relation to the roll, a supporting member for the outer end of the tubular member, a shaft in the tubular member and having its outer end extending beyond the outer end of the 30 tubular member, an ironer shoe support secured to the outer end of the shaft, a shoe on the shoe support, and means for oscillating the shaft whereby the shoe is moved into and out of contact with the roll.

35 5. In a device of the class described, a roll, means for rotating the roll, a shaft, a shoe connected to the shaft for movement therewith, means for oscillating the shaft whereby the shoe will be moved into and out of contact with the roll, manually operated means for breaking the connection between the shaft and the shoe, and automatic means for reconnecting the shaft and the shoe when the shaft is subsequently oscillated.

40 6. In a device of the class described, a roll, means for rotating the roll, a shaft, a shoe connected to the shaft for movement therewith, means for oscillating the shaft whereby the shoe will be moved into and out of contact with the roll, manually operated means for breaking the connection between the shaft and the shoe, and spring means for re-establishing the connection between the shaft and the shoe during a subsequent oscillation of 45 the shaft.

50 7. In a device of the class described, a roll, means for rotating the roll, a shaft, a shoe connected to the shaft for movement therewith, means for intermittently oscillating the 55 shaft whereby the shoe will be moved into and

out of contact with the roll, manually operated means for breaking the connection between the shaft and the shoe, means independent of said oscillating means for limiting the movement of the shoe after said connection is broken, and spring means for re-establishing the connection between the shaft and the shoe during a subsequent oscillation of the shaft.

70 8. In a device of the class described, a roll, means for rotating the roll, a shaft, a yoke pivotally mounted on the shaft, a shoe carried on the yoke, means for connecting the yoke to the shaft whereby oscillating movement of the shaft will cause the yoke to be moved towards and from the roll, such means including a member secured to the shaft, a spring pressed rod in one end of such member, a dog pivotally mounted on the yoke and adapted to engage a pin in one end of the rod, means for oscillating the shaft, manually operated means for moving the dog about its pivot to carry it out of engagement with the pin on the rod, and a spring connected to the dog to move the dog into engagement with the pin on the rod when the shaft is subsequently oscillated.

75 9. In a device of the class described, a roll, means for rotating the roll, a shaft, a yoke pivotally mounted on the shaft, a shoe carried on the yoke, means for connecting the yoke to the shaft whereby the movement of the shaft will cause the yoke to be moved toward and from the roll, such means including a member secured to the shaft, a rod slidably mounted in such member, a spring interposed between such member and the end of the rod, means for varying the tension of the spring, a dog pivotally mounted on the yoke in engagement with a pin in one end of the rod, means for oscillating the shaft, manually operated means for moving the dog about its pivot to carry it out of engagement with the pin on the rod, and a spring connected to the yoke and to the dog to move the dog into engagement with the pin on the rod when the shaft is operated after the manual manipulation of the dog.

80 95 In witness whereof I have hereunto set my hand this 20th day of September, 1929.

100 LUTHER RINGER. 115
